GARMENT HANGER

Robert H. Wollin, Milwaukee, Wis., assignor to
William J. Nesbitt, Milwaukee, Wis.

Application July 1, 1946, Serial No. 680,635

1 Claim. (Cl. 223—96)

1

This invention relates to improvements in garment hangers and more particularly to trouser and skirt hangers.

The principal object and purpose of my invention is to provide a garment hanger of a design which enables the garment clamping members of the hanger to be stamped from sheet metal, such as sheet steel, for rigidity and strength of the hanger and inexpensiveness of production.

A further object of my invention is to provide the hanger members in the form of stampings whereby the cross and neck portions of each member will be integrally connected and in substantially co-planar relation.

A further object of my invention is to provide the stampings in channel form with a marginal flange extending about each hanger member for strength, yet lightness in construction.

A further object of my invention is to connect the hanger members at the upper ends of the neck portions by an improved hinge means to be hereinafter described.

A further object of my invention is to provide the hanger members with opposed slots or ways and a key element slidably mounted therein to clamp the hanger members in closed or garment clamping relation.

The invention consists further in the structural features and combinations of parts herein-after described and claimed.

In the accompanying drawing—

Fig. 1 is a side elevational view of my improved garment hanger;

Fig. 2 is a vertical sectional view taken on line 2—2 of Fig. 1;

Fig. 3 is a vertical sectional view taken on line 3—3 of Fig. 1 through the upper portion of the hanger to show the details of the hinge means;

Fig. 4 is a horizontal sectional view taken on line 4—4 of Fig. 1 to show the stops on the hanger members for the hook element;

Fig. 5 is a longitudinal sectional view through the hinge means;

Fig. 6 is a horizontal sectional view through the neck portions of the hanger device to show the form of the locking key;

Fig. 7 is a vertical sectional view at the key taken on line 7—7 of Fig. 6; and

Fig. 8 is a fragmentary elevational view of a modified form of construction to be hereinafter described.

As shown in the drawing, the garment hanger of my invention comprises a pair of opposed garment clamping members 1, 1, each having a base portion 2 of a length to extend substantially

2

across the width of the garment portion clamped in the hanger and an upwardly extending neck portion 3. The hanger members 1 are symmetrical and are hinged together at 4 at the upper ends of the neck portions 3 so that the hanger may be opened and closed in the use of the device.

The hanger members 1 in accordance with my invention are each made in sheet or plate form with the base and neck portions 2, 3 of each member in co-planar relation and fixedly connected together at their juncture, as when each member 1 is fashioned in one-piece form from sheet metal or sheet steel in a stamping operation. This provides a relatively light and inexpensive hanger construction, yet sufficiently rigid and strong for the intended use of the device.

When produced as metal stampings, the hanger members 1 are given channel form, the members 1 being arranged in assembled relation with their channels 5 opposed and facing each other as shown in Fig. 6. The channels 5 extend throughout the extent of the members 1 and at the base portions 2 accommodate the felt or resilient pads 6 which are glued or otherwise fixed in place to provide yielding gripping surfaces for the hanger members to prevent slippage of a garment article clamped therebetween. The members 1 are clamped against the interposed garment article by a key 7 to be presently described.

The key 7 is slidably engaged with the neck portions 3 in slots or ways 8, 8 therein, there being one slot or way 8 in each neck portion 3, as shown in Figs. 1 and 6. The slots 8 are opposed and extend longitudinally or lengthwise of the respective neck portions 3 from adjacent their upper ends just short of the hinge 4 to adjacent or into their base or cross-portions 2 as shown in Fig. 1.

The key 7 is preferably made of metal or other desired rigid material and is slidable along the slots 8 in the opening and closing of the hanger members 1 as shown in Fig. 2, wherein the members 1 are shown in open and closed positions in dotted and full lines, respectively. The key 7 is moved to the upper ends of the slots 8 by the hanger members 1 as they are swung apart about the hinge 4 to open the hanger to release or receive a garment article. When the members 1 are swung towards each other to clamp the garment article therebetween the key 7 drops downwardly in the slots 8 until arrested by the divergent relation of the hanger members whereupon the key is forced further downward of the slots to tightly clamp the garment in the hanger.

The key 7 extends through the slots 8 as before

mentioned and has head portions 9, 9 at its opposite ends to extend across the slots on the outer sides of the hanger members 1. This retains the key 7 in connected relation with the slots 8 and provides means on the key to engage the neck portions 3 and force them to closed position to clamp the garment article therebetween. In this respect the inner edges 10, 10 of the head portions 9 have a camming action on the neck portions 3 and are beveled to coact easily therewith as the key is moved down the slots to tightly clamp the hanger members 1 on the garment.

The pads 6 when in contact with the garment article hold the neck portions 3 in a divergent relation from the hinge means 4 and the key 7 has a wedging action thereon to increase the clamping pressure on the garment article as the key is forced downwardly on the neck portions 3. The inner edges 10, 10 of the heads 9 of the key are curved or deflected outwardly to confine the contact of the heads 9 with the outer surfaces of the neck portions 3 along the edges of the slots 8. This prevents the heads 9 of the key 7 scraping off the coating on the neck portions 3 in the sliding movement of the key.

The hanger device has a hook element 11 at its upper end to support the device with or without a garment from an overhead support in a closet, wardrobe or the like. The hook element 11 is connected to the hinge means 4 to be presently described.

The mid-portion 12 of the key 7 is generally rectangular and has a dimension to extend through the slots 8 with sufficient clearance for ease of movement of the key along the slots. The non-circular shape of the mid-portion 12 keeps the key from turning in the slots 8 and, hence, the key is maintained in operative connection at all times with the neck portions 3.

The hinge means 4 comprises a hinge pin 13 mounted in ears 14 on the flanges 15 along the outer edges of the hanger members 1 about the channels 5. These flanges 15 extend inwardly and strengthen the hanger members 1 and enable them to be made of relatively thin gauge sheet metal for lightness in weight of the hanger device as a whole. The ends of the pin 13 are upset to hold the pin in place.

Rotatably mounted on the pin 13 between the ears 14 is a sleeve 16 to which the hook element 11 is fixed. The sleeve 16 enables the hook 11 to be swung laterally, the extent of this movement being limited by the upper portions 15a of the flanges 15 along the sides of the sleeve 16 as shown in Figs. 3 and 4. It will be noted in Fig. 4 that the flange portions 15a have notches 17 to receive the hook element 11 at the extremes of its lateral movement.

The hanger members 1 may be provided along the slots 8 with a series of notches 18 which hold the key 7 in its several locking positions along the slots 8. This guards against accidental slipping of the key from its locking positions. The heads 9 of the key 7 engage in the notches 18.

This modification is shown in Fig. 8 where the slot is indicated as 8a and the key as 7a.

The hanger device shown and described is simple and inexpensive in construction and being comprised of a design which may be stamped from sheet metal may be produced most economically. The hanger members 1 at the juncture of the portions 2, 3 are given curved form as shown in Fig. 1 to enhance their appearance.

The details of construction and arrangement of parts shown and described may be variously changed and modified without departing from the spirit and scope of my invention, except as pointed out in the annexed claim.

I claim as my invention:

A garment hanger of the character described comprising, a pair of garment members, each having a base or cross-portion and an upwardly extending neck portion, said hanger members having inwardly extending marginal flanges to give the hanger members channel form, said flanges continuing to the upper ends of the neck portions and there provided with overlapping ear portions, a hinge pin extending through said ear portions and fixed thereagainst to hingeably connect the hanger members together, said members having substantially co-planar outer surfaces co-extensive with the hanger members and extending to the extreme upper ends of the neck portions, the latter having substantially centrally disposed slots therein extending lengthwise of the neck portions from just short of said hinge pin to said cross-portion, a key element having a substantially rectilinear shank extending through said slots with a non-rotative fit therein and provided at its opposite ends with rectilinear heads extending cross-wise of the slots and laterally beyond the same, said heads being engageable with the outer sides of the neck portions along the slots and having inclined surfaces complementary to the angularity of the neck portions to move the garment members into clamping relation in the movement of the key element towards the cross-portion of the hanger members, a sleeve revolvably mounted on the hinge pin and having its ends opposed to the ear portions, and a hook member fixed to the sleeve for suspending the hanger member from an overhead support, said flanges at the upper ends of the neck portions being substantially parallel to the sleeve and limiting the lateral swing movement of the hook member.

ROBERT H. WOLLIN.
